UNITED STATES PATENT OFFICE

JOHN C. SPENCE, OF WORCESTER, MASSACHUSETTS, ASSIGNOR TO NORTON GRINDING COMPANY, OF WORCESTER, MASSACHUSETTS, A CORPORATION OF MASSACHUSETTS.

GRINDING-MACHINE.

1,121,773.

Specification of Letters Patent. Patented Dec. 22, 1914.

Application filed July 11, 1913. Serial No. 778,448.

To all whom it may concern:

Be it known that I, JOHN C. SPENCE, a citizen of the United States, residing at Worcester, in the county of Worcester and 5 State of Massachusetts, have invented a new and useful Grinding-Machine, of which the following is a specification.

This invention relates to grinding machines of the class in which provision is 10 made for feeding the grinding wheel transversely relatively to the work.

The invention is designed primarily as an improvement upon grinding machines of the type disclosed in the patent to Norton, No. 15 762,838, issued January 14, 1904, and has to do with an improved automatic cross feed for such a machine. The machine shown in the Norton patent is provided with an automatic cross feed which is connected to a 20 reversing lever operated by adjustable dogs upon the longitudinally movable work carriage. As the carriage approaches the end of its travel in either direction, the lever is reversed by one of the dogs and each 25 movement of the lever in either direction operates the cross feed to move the grinding wheel toward the work. Upon certain classes of work, however, it is found desirable to feed the wheel directly forward into 30 the work while the latter is held in fixed longitudinal position relative to the wheel. Under these conditions the dogs are inoperative and it is necessary to depend entirely upon manual actuation of the cross feed. 35 This necessitates the constant attendance of an operator for each machine and materially increases the cost of operation.

The object of my invention is to provide a grinder in which the cross feed may be 40 automatically operated independently of the longitudinal travel of the work carriage.

My invention further consists of certain devices, combinations and arrangements of parts hereinafter described and claimed, the 45 advantages of which will be obvious to one skilled in the art.

A preferred form of my invention is shown in the drawings in which—

Figure 1 is a front elevation of a grinding machine having my improvements at-

tached thereto: Fig. 2 is an enlarged view of the cross feed operating mechanism: Fig. 3 is a sectional detail view on the line 3—3 of Fig. 2: and Fig. 4 is a partial sectional view showing the connections to the 55 grinding wheel carriage.

Referring to Fig. 1, my invention is shown in connection with a machine in which the work carriage 10 is longitudinally movable and has mounted thereon adjustable dogs 11 and 12. These dogs as they approach the end of their travel contact with a reversing lever 13 mounted to turn about a pivot 14. The reversing lever 13 has rigidly secured thereto a curved arm 15 (see Fig. 2) to which is adjustably secured a sleeve 16. Pivotedly connected to an extension on the sleeve 16 is a rack 17 meshing with a pinion 18. The pinion 18 is secured to a disk 19 bearing a crank pin 20. 60 A feed pawl 21 is mounted upon an arm 22 which swings freely about the shaft 23. The pawl 21 is pivotally connected by the crank pin 20 to the disk 19 and is moved thereby to feed the pick wheel 24 which is connected through suitable gearing with the feed screw 25 which turns in a threaded nut 26 mounted below the grinding wheel carriage 27.

The parts thus far described form no part 80 of my invention, and a more complete disclosure thereof may be found in the patent to Norton, No. 762,838.

Referring to Fig. 2, the curved arm 15 on the reversing lever 13 is provided with a 85 downward extension 28 bearing a stud 29. Detachably connected with the stud 29 is a link 30 provided at one end with an open-ended slot, the other end of said link being secured to the vertical arm 31 of a bell crank 90 mounted on the stud 32. The horizontal arm 33 of the bell crank is connected to a coil spring 34 which yieldingly forces the link 30 toward the left (as viewed in Fig. 2). The vertical arm 31 of the bell crank 95 is provided with a horizontally projecting stud 35 (see Fig. 3) which engages a side cam 36 mounted upon the main feed shaft 37.

In the normal operation of the machine, the table 10 is actuated to travel longitu-

dinarily thereby bringing the dogs 11 and 12 alternately into contact with the reversing lever 13 and moving the rack 17 alternately in opposite directions. Each movement thereof actuates the feed pawl 21 to move the grinding wheel carriage toward the work.

It is evident, of course, that when the longitudinal travel of the work carriage is discontinued the mechanism just described will no longer operate. Under these conditions the detachable link 30 may be connected with the stud 29 and the constantly rotating cam 36 will then operate through the bell 15 crank 31 and the link 30 to oscillate the reversing lever and to thus automatically operate the cross feed independently of the longitudinal travel of the work carriage.

A bracket 38 (see Fig. 2) is provided in 20 which the link 30 may rest when disconnected from the stud 29. A handle 39 (see Fig. 4) is also provided by which the cross feed may be manually operated.

I am aware that many modifications of 25 my device may be made by those skilled in the art without departing from the spirit and scope of my invention and I do not wish to be limited to the details disclosed herein, but

30 What I do claim is:

1. In a grinding machine, in combination a cross feed for the grinding wheel, automatically actuated driving means for said cross feed and auxiliary driving means for 35 said cross feed automatically actuated independently of the first mentioned driving means.

2. In a grinding machine, in combination a cross feed for the grinding wheel, manual 40 means for actuating said cross feed, automatic means dependent on the work feed for actuating said cross feed, and auxiliary automatic means independent of the work feed for actuating said cross feed.

45 3. In a grinding machine, in combination a grinding wheel, a cross feed for said grinding wheel, automatic means controlled by the longitudinal travel of the work carriage for driving said cross feed and a second automatic means operating independently of the travel of the carriage for driving said cross feed.

4. In a grinding machine, in combination a cross feed for the grinding wheel, automatic means for actuating said cross feed, auxiliary means for actuating said cross feed, and detachable connections between 55 said auxiliary mechanism and said automatic means.

60 5. In a grinding machine, in combination a cross feed for the grinding wheel, automatic means for actuating said cross feed and auxiliary mechanism for actuating said cross feed, said auxiliary mechanism being

operated positively in one direction and 65 yieldingly in the opposite direction to drive the cross feed independently of the first mentioned actuating means.

6. In a grinding machine, in combination a cross feed for the grinding wheel, an oscillating reversing lever adjustably connected 70 to actuate said cross feed, a longitudinally movable work carriage, means on said carriage to oscillate said lever and auxiliary means operating independently of the carriage 75 for oscillating said lever.

7. In a grinding machine, in combination a cross feed for the grinding wheel, an oscillating reversing lever, adjustable connections from said lever to said cross feed, a 80 rotary shaft having a cam thereon, a cam follower yieldingly engaging said cam, and connections between said cam follower and said lever whereby the rotating cam may actuate the cross feed.

8. In a grinding machine, in combination a cross feed for the grinding wheel, operating mechanism therefor, including an oscillating lever having a downward extension bearing a projecting stud, a cam-operated 90 arm, and a link pivoted to said arm and having at its other extremity an open-ended slot for detachably engaging said stud.

9. In a grinding machine, the combination with the bed or support, a grinding 95 wheel or disk movable laterally on said support toward and from the work, a work table having a reciprocating motion at right angles to said grinding wheel, driving gear for operating said work table, and mechanism for adjusting said grinding wheel in 100 relation to the work, operable either from the reciprocating work table or from the driving gear independently of the work table, substantially as described.

10. In combination in a grinding machine, a work table having reciprocating movement, a grinding wheel, driving means for the work table, means for adjusting the grinding wheel in a direction transversely 110 of the work table and an operating connection for said adjusting means operable either from the reciprocating carriage or the driving gear, substantially as described.

11. In combination in a grinding machine, driving means, a work holding table, means for reciprocating same, a grinding wheel, a rack bearing arm, mechanism operated thereby to adjust said grinding wheel in relation to the work, means for operating 120 said rack by the reciprocating of the work table, and means for operating the rack from the driving means of the machine independently of the said work table or slide, substantially as described.

12. In combination in a grinding machine, driving means for same, a reciprocating work holding table, a grinding wheel,

a rack bearing arm or member, means operated thereby to adjust said grinding wheel in relation to the work, said rack bearing arm being operable either from the work 5 table or by said driving means, substantially as described.

In testimony whereof I have hereunto set

my hand, in the presence of two subscribing witnesses.

JOHN C. SPENCE.
